his Attorney

UNITED STATES PATENT OFFICE.

ARTHUR RICE, OF NEW ALBANY, INDIANA, ASSIGNOR TO THE PEERLESS MANUFACTURING COMPANY, OF LOUISVILLE, KENTUCKY.

SAND MOLDING-MACHINE.

SPECIFICATION forming part of Letters Patent No. 340,362, dated April 20, 1886.

Application filed January 20, 1886. Serial No. 189,132. (No model.)

To all whom it may concern:

Be it known that I, ARTHUR RICE, a citizen of the United States, residing at New Albany, in the county of Floyd and State of Indiana, have 5 invented certain new and useful Improvements in Sand Molding-Machines, of which the following is a full, clear, and exact description.

This invention relates to certain improvements in that class of machines for making molds for casting represented in United States Letters Patent Nos. 322,202, granted July 14, 1885, and 332,834, granted December 22, 1885.

The improvements consist in the drawer for filling the mold with sand, and means for operating the said drawer, and means for venting the flask, all as I will now proceed to particularly set forth and claim.

In the accompanying drawings, in the several figures of which like parts are similarly 20 designated, Figure 1 is a side elevation, partly in section, of one form of my invention. Fig. 2 is a similar view of another form; Fig. 3, a cross-section in the plane of line $x-x$ of Fig. 2 on a larger scale; and Fig. 4 is a bottom view 25 of the binder on another scale.

The sand-hopper a , its supporting-frame b , and the molding-machine c may be of any preferable construction. The bottom of the sand-hopper is provided with a chamber, in 30 which is arranged the sand-drawer d in such a manner that such drawer constitutes a movable bottom for the hopper, substantially as in my Patent No. 332,834.

The drawer d is preferably of metal, and 35 along the upper edge of each side it is provided with a flange, e , projecting outwardly at right angles from the same, by means of which flanges e the drawer is supported and movable upon rollers f , secured to the frame b . 40 The drawer is divided into two compartments, and in the form shown in Fig. 1 the front compartment, g , is bottomless and receives the sand from the hopper, and conveys it to and deposits it in the flask on the molding-machine. The rear compartment, h , in all cases 45 has a closed top, i , which serves as a valve to shut off the escape of sand from the hopper when the drawer is projected over the flask.

In Fig. 1 the bridge j is hung in brackets k 50 between the hopper and the molding-machine, and said bridge is of a width to span the space between the hopper and molding-machine.

Said bridge is weighted or otherwise constructed to stand upright, and is in this position so near to the hopper that when the front end of the drawer clears the hopper in moving out it will strike the bridge and bring it into a horizontal position to cover the space between the hopper and molding-machine, 55 and thus aid the compartment g of the drawer in carrying its load of sand from the hopper and deposit it in the flask. The drawer works from a stationary platform, l , interposed between the hopper and its frame b , which platform serves as a bottom for the drawer when its compartment g is under the hopper. 60

The drawer is moved back and forth by means of a return-screw, m , mounted in the frame b and suitably driven. The drawer is 70 connected to this return-screw by a rod, n , attached to the rear end of the drawer and jointed to a traveler, o , which is supported by flanges p in ways r , attached to the frame b , and this traveler o is provided with a swiveling, s , which engages the threads of the return-screw to transmit the motion of the screw to the traveler. 75

It will be seen that in operation when the binder t is thrown back and the flask u is in 80 position the rotation of the return-screw will carry the traveler, and consequently the drawer, toward the flask, and inasmuch as the drawer is in advance of the traveler by the length of its compartment g , said compartment will be 85 fully over the flask at the time the traveler has reached the end of its travel in one direction, having reached which the traveler begins its return journey, and immediately carries the drawer back under the hopper to receive a 90 fresh charge of sand for another flask. If desired, automatic stops may be provided for arresting the drawer both at its forward and return movements; but I make no claim to such devices at this time. 95

In the form shown in Fig. 2 the compartment g of the drawer has a movable bottom, v , which is supported and travels upon rollers w , fixed to the sides of the drawer. This bottom v is connected to the rod n , which is operated from the return-screw m through the traveler o , as in the former example, the said bottom being provided with a stop, y , to engage a partition between the compartments g and h of the drawer. The rod n is provided 100 with a slot, n' , of a length equal to the dis- 105

tance between the molding machine and hopper. Grooved or other shaped guards, a' , preferably of sheet metal, are interposed between the sides of the compartment g and the top 5 surface of the bottom v , in order to cover the joint between the bottom and sides. The guards may be riveted or otherwise attached to the sides of the drawer.

In this form of drawer the engagement of o the stop y with the drawer carries the drawer and the bottom in place under the compartment g over the flask, the bottom sustaining the load of sand in the compartment. When the drawer covers the flask, the traveler has 5 reached the end of its forward movement, and begins its return movement, carrying back the bottom and letting the sand drop freely into the flask to fill it uniformly and evenly; but it will be noticed that the traveler moves the o distance of the slot n' before it is effective in moving the bottom, so that when said traveler has reached the end of its return movement the bottom will not be fully retracted, but will cover the space between the hopper and the 5 molding-machine, thus preventing the loss of sand at that point. When the flask is filled, the drawer is pushed back in place under the hopper by hand, and when the partition between its two compartments reaches the stop o y the bottom will be also carried back with the drawer, and placed in the position indicated in Fig. 2.

In the form of machine shown in Fig. 2 the bottom serves as or takes the place of the 5 bridge j in spanning the space between the hopper and the molding-machine.

In operating sand molding-machines of the character herein referred to it has been found that the face of the sand in the flask, when o compressed, was curved outward to a greater or less degree, notwithstanding the fact that the compressor device and the binder were perfectly flat. It has been determined that this resulted from the springing of the binder, 5 and no amount of stiffening of the binder has so far been effective in overcoming this difficulty. I have found by allowing a vent at the upper part of the flask for the escape of confined air this objection was overcome. To afford such a vent, I have provided the binder t with projections t' at points next to the flask, or such projections may be made upon the flask. With this construction, during the process of compressing the confined air makes 5 its way through the sand, leaving passages, which form complete vents for the escape of the gases when the molten metal is poured into the molds in casting.

The binder otherwise is constructed and applied to the machine substantially as in my Patent No. 332,834.

It is not original with me to automatically move the sand-drawer of a molding-machine from the hopper to the flask and back again, 5 and hence my invention in this particular consists in the new combination of the old return-screw with the removable drawer, as herein-

after particularly claimed. Furthermore, the provision of vent-holes in the binder of a molding-machine is not original with me, and 70 with reference to this feature my invention resides in providing projections at the corners to separate the binder and flask sufficiently to vent the flask. Heretofore, in order to get a square fit of the binder on the flask, so as to 75 prevent warping and other evil consequences of a bad fit, the meeting parts had to be planed down level at great cost of time and considerable outlay of money, and with not always satisfactory results. By using the corner projections I not only vent the flask, but in order 80 to get a square fit of the parts have only a few square inches to plane instead of several square feet, and always insure a perfect fit.

What I claim is—

1. In a sand molding machine of substantially the construction set forth, a sand-hopper and a drawer beneath it for conveying a charge of sand from the hopper to the flask to be filled, combined with means for moving 90 such drawer when filled from the hopper to the flask and returning it to the hopper when its charge has been deposited in the flask, the same consisting of the return-screw m , the traveler o , arranged in suitable guides on the 95 frame of the machine and engaging the thread of the return-screw to be traversed back and forth therein, and the rod n , connecting the traveler and drawer to transmit the motion of the return-screw through the traveler to the 100 drawer, substantially as and for the purpose specified.

2. In a sand molding-machine, a sand-hopper, a sand-drawer arranged therein, means to move it to carry the charge of sand to the 105 flask, and a movable bottom for said drawer supported on holders attached to the drawer, and guards secured to the sides of the drawer and covering the space between the drawer and its bottom, combined substantially as described. 110

3. In a sand molding-machine, a sand-hopper provided with a movable drawer, an independently-movable bottom for said drawer, and a return-screw, combined with a traveler, 115 and a slotted rod connecting the traveler and bottom, and a stop connecting the drawer and bottom, substantially as and for the purpose described.

4. The combination, in a sand molding-machine, of a flask to receive the charge of sand, 120 and a binder to cover the flask while molding or compressing the sand, and projections t' , interposed between the flask and binder, to separate the two sufficiently to vent the flask 125 while the compression of the sand is going on, substantially as described.

In testimony whereof I have hereinunto set my this 18th day of January, A. D. 1886.

ARTHUR RICE.
